US00D948331S

(12) **United States Design Patent** (10) **Patent No.:** **US D948,331 S**
(45) **Date of Patent:** **** Apr. 12, 2022**

(54) **CONTAINER**

(71) Applicant: **Kraft Foods Group Brands LLC**,
Chicago, IL (US)

(72) Inventor: **Michael D. Putnam**, Chicago, IL (US)

(73) Assignee: **Kraft Foods Group Brands LLC**,
Chicago, IL (US)

(**) Term: **15 Years**

(21) Appl. No.: **29/658,520**

(22) Filed: **Jul. 31, 2018**

(51) LOC (13) Cl. **09-03**

(52) U.S. Cl.

USPC **D9/425**

(58) **Field of Classification Search**

USPC D7/400, 601, 608; D9/416, 417, 420,
D9/425-429, 430, 432, 761
CPC . B65D 1/26; B65D 1/40; B65D 5/243; B65D

OTHER PUBLICATIONS

Mintel Report; undated; in existence at least as early as Aug. 21, 2017; 80 pages.

Primary Examiner — Janice Patyk

(74) Attorney, Agent, or Firm — Fitch, Even, Tabin & Flannery LLP

(57) **CLAIM**

The ornamental design for a container, as shown and described.

DESCRIPTION

FIG. 1 is a top perspective view of embodiment one, of a container, showing my new design.

FIG. 2 is a top plan view thereof.

FIG. 3 is a front elevation thereof, the rear elevation being identical.

FIG. 4 is a right side elevation thereof, the left side elevation being identical.

FIG. 5 is a bottom view thereof.

FIG. 6 is a top perspective view of embodiment two, of a container, showing my new design.

FIG. 7 is a top plan view thereof.

FIG. 8 is a front elevation thereof, the rear elevation being identical.

FIG. 9 is a right side elevation thereof, the left side elevation being identical; and,

FIG. 10 is a bottom view thereof.

1 Claim, 6 Drawing Sheets
